CLAIM

The ornamental design for a cookware assembly, as shown and described.

DESCRIPTION

FIG. 1 is a front perspective view of a cookware assembly showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines immediately adjacent to the shaded area define the bounds of the claimed design and form no part thereof. The broken lines depicting the remainder of the cookware assembly form no part of the claimed design.
